MANUFACTURE OF WIRE-DRAWING DIES

Elmer B. Welch, McKeesport, Pa., assignor to
Firth-Sterling Steel Company, a corporation of
Pennsylvania

Application May 2, 1939, Serial No. 271,318

3 Claims. (Cl. 219—3)

This invention relates to the manufacture of wire-drawing dies, and consists in a method of producing such dies. The object in view is a die of superior quality, more certainly secure against accidental breakage, and, accordingly (the average product being considered) of enhanced durability.

In the accompanying drawing Fig. I is a view partly in elevation, partly in vertical and axial section, of a press and of the parts that go to make up the die assembly in position in the press, ready to be acted on; Fig. II is a like view of the same collocation, after the press has operated upon the parts in place within it; Fig. III is a view in perspective of the nib of the die, before assembly with its carrier; Fig. IV is a view in perspective of the completed die; and Fig. V is a view in axial section of a finished die.

A wire-drawing die includes a nib and a carrier. The nib is formed of a very hard metal composition of relatively high melting-point—such a composition, for example, as may be prepared by sintering a mixture of a hard metal carbide with a binding metal, such as cobalt. The nib is essentially a small cylindrical body having (ultimately) an axial perforation through it. It is initially prepared for the purposes of this invention as a cylindrical block 2 (Fig. III) having in one head a central conical recess, 15, but being otherwise integral. The carrier is a 20 heavy walled casing, and consists essentially of a cylindrical block of softer metal (and of lower melting-point) having an axial bore of diameter sufficient to receive the nib. The bore is shouldered within, and upon the shoulder the nib 25 rests and in such position the nib is secured to its carrier. The casing serves to carry the nib and in the wire-drawing operation to re-enforce the nib, and to prevent the cracking of the nib under the stresses of service.

It has heretofore been proposed to mount such a wire-drawing nib in a steel casing by assembling the nib within a sleeve of steel, heating the assembled nib and sleeve, and then placing the assembly in a die and forging or rolling it 45 so as to fold the upper edge of the sleeve over the nib and so to lock the nib in place. Other methods such as shrinking and pressing of the nib in place are also used.

I have found that, in forging or rolling a steel 50 sleeve around the nib in this manner, the portion of the sleeve which is folded over or upset over the nib is strained, and is likely on cooling to crack the nib or to be cracked itself. Great care must also be exercised in fitting the 55 nib to the steel sleeve. Wire-drawing dies are subject to great pressures during use, and unless the hard metal carbide is reinforced by intimate contact with its sleeve throughout all adjacent portions, there is danger that the nib will crack 60

in service. Shrinking and pressing of the nib into place also require very close work in fitting, and there is danger of cracking the nib and the sleeve in the operation.

5 Another method of preparing the assembly of nib and carrier is that proposed in the Schultz patent, No. 1,922,178, a patent that is owned by the company by which I am employed and to which the invention of this application is this day assigned. According to that method the tungsten-carbide nib is placed in a mold cavity, and a suitably compounded iron is cast around it to form the carrier, embedding the nib within the cast metal body. My company has encountered difficulty in centering the nib in the mold in following the Schultz method. The nib has a tendency to be forced off center when the melted iron is poured into the mold. Another disadvantage of this method is that blow-holes are likely to form in the casing, particularly at the surfaces of contact with the nib. This results in an insufficient support for the nib. The formation of holes or porosity in the cast-iron casing, when operating according to the Schultz 10 teaching is believed to be due largely to the fact that when the molten cast iron makes contact with the cold nib within the mold, gases are released which are entrapped in the cast iron, particularly at the surfaces of the contact with the nib. Furthermore, if any of the cast iron spatters in the pouring and falls upon the cold nib, it solidifies immediately, forming pellets that may not be completely liquified and merged with the remainder of the cast iron as it is poured into and fills the mold; and this may 15 result in imperfections in the casing metal.

According to the present invention a nib 2 is provided that in this blank stage may, as has been said, consist merely of a small cylindrical block 20 having a small conical depression sunk centrally in one of the heads of the cylinder. This block may be formed of tungsten carbide bonded with cobalt, or of another hard metal composition, of high melting-point. The carrier 2 is essentially a cylindrical block of relatively soft metal, of relatively low melting-point, such as steel, copper, or modified cast iron. The modified cast iron that I prefer for this purpose is that known commercially as Meehanite. It is a product of methods described in United States patents, Nos. 1,499,068; 1,683,086; 1,683,087; and 1,731,346. It is obtained by adding to the better grades of molten commercial cast iron a small amount of a silicide of an alkaline earth metal, such as calcium or magnesium, or by adding metallic calcium. This cylindrical carrier block 4 is penetrated by an axial bore that from the upper face of the block downward (as seen in Fig. I) is cylindrical, and of a size snugly to receive, when the parts are

cold, the nib 2. This cylindrical portion of the bore is of greater extent longitudinally than the length of the nib; it terminates in an inward extending ledge or shoulder; and from this ledge or shoulder the bore continues with downward flare, as Fig. I shows.

The nib 2 is introduced into the bore of the block 4 and rests upon the ledge with that head uppermost that bears the central conical depression, as shown in Fig. I.

A press is provided whose members 9, 9 are electrodes in an electric circuit of suitable current strength and voltage, and, as is conventional in such case, these electrodes are of copper and are water cooled. They are faced with work-engaging blocks 5 and 11, of graphite. The graphite blocks 5 and 11 have work engaging faces that carry in relief a certain design—in this case circular bosses or projections 50 and 110, respectively, somewhat less in diameter than the heads of the block 4, and these bosses are encircled by steps or shoulders of less eminence. Thus the blocks are mold members, or die members, whose function in this respect will presently be made more clear.

Both blocks 5 and 11 are axially perforate and in the perforations are set pins 7 and 13 (also of graphite) and of such snug fit within the perforations as to be carried frictionally and to slide in the perforations when in the pressing operation stress is exerted upon them. Normally they project from the perforations in the blocks 5 and 11. At their ends they are shaped, the pin 7 to register with the flaring lower end of the bore through block 4, the pin 13 to register with the conical depression 15 in the head of nib 2.

The assembly of block 4 and nib 2 is brought to place in the press and the press is closed, the pin 7 in engagement with the bore in block 4, the pin 13 in engagement with the depression 15. Thus the assembly is trued and held true in the ensuing operation. The press is closed, and contact is established by pressure. Current is then turned on, and this current, flowing through the central body portion of the block 4 (the body portion that extends immediately between the bosses 50 and 110 of the work-engaging blocks 5 and 11), heats the central body portion of the block 4 until it comes to a semi-molten or plastic condition. (The outer side wall of the block 4, exposed to the cooling effect of the surrounding atmosphere, remains rigid.) Under pressure (increased if need be) the substance of block 4 (within such rigid side wall) is minutely shaped. The walls of the bore close upon the adjacent walls of nib 2, in a bond that is intimate and continuous, and without fault or flaw; the bore above the nib closes in upon the pin 13, forming an annular shoulder 16 that overhangs the upper head of the cylindrical nib 2; and the bosses upon the faces of the blocks 5 and 11 sink into the surfaces of the heads of block 4, forming centered countersunk recesses. The boss-encircling depressions upon the faces of blocks 5 and 11 provide clearance for the upper and lower peripheries of the rigid side-wall portion of the block, and form at the margins of the heads of the block 4 desired upstanding rims. These operations of shaping and die-casting will be understood on comparing with Fig. I (which shows the initial positions) Fig. II (which shows the ultimate positions).

In the operations as I have conducted it I have

employed with success a current of from 2,000 to 10,000 amperes on the secondary, using a 120 kva. transformer, 60 cycle, 1 phase, with a primary of 115, 230, and 330 volts.

5 When the press is opened the die is removed. It consists of a cylindrical carrier with outstanding terminal rims 17, and having an axial bore within whose walls is embedded and bonded the accurately aligned nib 2. It remains only to 10 shape in conventional manner the eye 18 through the nib, through which the wire-drawing operation is effected.

I claim as my invention:

15 1. The method herein described of mounting a wire-drawing nib within the bore of a metal casing which consists in assembling a nib that is less in longitudinal extent than the length of the bore within and at the bottom of the bore in the casing, mounting the casing between two electrodes, the electrodes engaging the opposite heads or ends of the casing, causing an electric current to pass between the electrodes and through the central body portion of the casing while exteriorly subjecting the casing to the influence of a cooling medium, whereby the substance of the casing 20 is softened interiorly while exteriorly it remains rigid, and subjecting the so conditioned casing, in the centrally heated body portion, to compression in the direction of the axis of the bore, whereby the walls of the bore close upon the contained nib, making intimate contact with the adjacent walls of the nib.

25 2. The method herein described of mounting a wire-drawing nib within the bore of a metal casing which consists in assembling a nib that is less in longitudinal extent than the length of the bore within and at the bottom of the bore in the casing, mounting the casing between two electrodes, the electrodes engaging the opposite heads or ends of the casing, causing an electric current to pass between the electrodes and through the central body portion of the casing while exteriorly the casing is subject to the cooling influence of the surrounding air, whereby the substance of the casing 30 is softened interiorly while exteriorly it remains rigid, and subjecting the so conditioned casing, in the centrally heated body portion, to compression in the direction of the axis of the bore, whereby the walls of the bore close upon the contained nib, making intimate contact with the adjacent side-walls of the nib and overhanging the upper end-wall thereof.

35 3. The method herein described of preparing the assembly of a wire-drawing nib and its carrier, which consists in seating in the shouldered axial bore of a cylindrical metallic block the pre-formed nib, mounting the block between two electrodes, the electrodes engaging the opposite heads of the cylindrical block and the block-engaging faces of the electrodes bearing a design in relief, causing an electric current to pass between the electrodes and through the block, while exteriorly the block is subject to the cooling influence of the surrounding air, whereby the substance of the block 40 is softened interiorly while exteriorly it remains rigid, and exerting pressure upon the so conditioned block through the electrodes and thereby closing the walls of the bore of the block upon the adjacent surfaces of the contained nib 45 and impressing upon the heads of the cylindrical block the designs upon the faces of the electrodes.
